BY *John A. Giedersheim*, ATTORNEY.

UNITED STATES PATENT OFFICE.

JOSEPH LOEB, OF PHILADELPHIA, PENNSYLVANIA.

DESIGN FOR FRINGE.

SPECIFICATION forming part of Design No. 13,590, dated February 6, 1883.

Application filed December 16, 1882. Term of patent 3½ years.

To all whom it may concern:

Be it known that I, JOSEPH LOEB, a citizen of the United States, residing in the city and county of Philadelphia, State of Pennsylvania, have invented and produced a new and original Design for Fringe, of which the following is a specification, reference being had to the accompanying drawing, forming part thereof.

The accompanying drawing is a face view of a section of fringe embodying and illustrating my design, which consists of a fringe having a heading, A, of any suitable kind, to which are attached at intervals two series of chenille pendants, B B'. The middle portion of each pendant is formed of a plain block, which in the pendant B is of different shade from that in the pendant B', so that there is a variation of shade or alternation of different shades in the two series of pendants. The portions of each pendant, respectively, above and below the middle block are formed of blocks or stripes of different colors, thus presenting throughout the length of the fringe upper and lower striped bands, the shade of the band in the pendant B being different from that of the band in the pendant B', so that there is a variation of shade or alternation of different shades in the length of each striped band.

The end tips, a, may or may not form parts of the design.

I do not confine myself to the use of any given colors or material.

I claim—

1. A design for a fringe consisting of a heading and a series of chenille pendants, each of which has at its middle a plain block, the middle blocks throughout the fringe being alternately of different shade, substantially as set forth. 35
2. A design for a fringe consisting of a heading and a series of chenille pendants, having upper and lower striped bands, the shade of which is different in alternate pendants, substantially as set forth. 40
3. A design for a fringe consisting of a heading and a series of chenille pendants, each of which has at its middle a plain block, the blocks being alternately of different shade, and upper and lower striped bands, the shade of which is different in alternate pendants, substantially 45 as above set forth. 50

JOSEPH LOEB.
